UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE.

1,217,215.

Specification of Letters Patent. Patented Feb. 27, 1917.

Application filed June 15, 1915. Serial No. 34,277.

To all whom it may concern:

Be it known that I, ADAM H. PRENZEL, a citizen of the United States, residing at Halifax, in the county of Dauphin and State 5 of Pennsylvania, have invented certain new and useful Improvements in Shoes, of which the following is a specification, reference being had therein to the accompanying drawing.

10 The present invention relates to improvements in shoes and has for its object to improve the construction of shoes as regards durability, comfort, cheapness, water proofing qualities and to prevent squeaking and 15 drawing.

Present day shoe constructions are unsatisfactory in that the filler structure between the inner and outer soles does not retain its shape in use but shrinks, shifts, and bunches, 20 with the result that the tread portion or support for the foot becomes uneven and irregular, the set and shape of the shoe is seriously affected, and a space is left between the parts permitting the entrance of moisture into the shoe. Furthermore, the materials of the filler injure the leather, stitching, and adjacent fabric, and weaken or rot 25 the same, destroying the connection between the parts. It has heretofore been proposed to provide shoes with fillers of a waxy nature, which are usually applied hot or require the presence of heat for the application thereof to the shoe bottom. In practice these have been found wanting in that 30 they injure the leather, stitching, and adjacent fabric of the shoe, that they shrink leaving a space between the parts and that they are sensitive to heat and in use become soft and lose their shape. Shoes provided 35 with fillers that contain rosin, resinous products, or vegetable oils, have a tendency to make shoes squeak, and the use of rosin and tarry and pitchy substances cause the shoe to draw the feet.

5 My invention provides an improved shoe having set in between the inner and outer soles and firmly united therewith, a layer of cheap, elastic substance, water repellent, non-shrinkable, not permanently conformable to localized pressures, unaffected by cold or any reasonable degree of heat, that is not in any way harmful to the leather, stitching, and adjacent fabric, that will not cause the shoe to draw the feet, and that will

55 prevent squeaking, a non-shiftable, permanently even, resilient tread or support for the foot being thus afforded throughout the life of the shoe, and the water proofing qualities, durability and pliability of the shoe being materially increased.

60 The invention will be understood from the following detailed description when considered in connection with the accompanying drawing, forming a part hereof, and wherein I have shown, by way of example, one embodiment of the invention, and have also 65 illustrated certain defects of prior constructions.

In the drawings:

70 Figure 1 is a bottom plan view of a shoe constructed in accordance with the present invention before the outer sole has been secured in place;

Fig. 2 is a side elevation of the completed 75 shoe with parts shown in section;

Fig. 3 is a transverse section taken on the line 3—3 of Fig. 2, the parts being shown on an enlarged scale; and

Fig. 4 is a transverse section of a shoe 80 construction commonly employed and illustrating how the filler structure thereof shrinks, shifts, and bunches in use.

Referring to the drawings in detail, 1 designates the upper, 2 the inner sole, and 3 the outer sole. Set in the cavity of the insole 85 between the soles and firmly united thereto, is a layer 4 of elastic substance. The layer 4 consists of rubber solution, a large proportion of filling material such as comminuted cork or cork dust, a vulcanizing material 90 such as sulfur, gutta percha and carbon tetrachlorid. A coloring material, such as Venetian red or sun set lamp black may also be included. The rubber solution is formed by dissolving rubber in a volatile solvent, 95 such as benzol, high grade gasoline, or naphtha, or like solvent. The rubber solution is placed in a mixing machine with the comminuted filling material, the vulcanizing material, gutta percha, coloring matter and 100 carbon tetrachlorid, and the whole thoroughly mixed and kneaded together, the carbon tetrachlorid being added before the completion of the mixing operation before removing the mixture from the mixing machine. The mixture thus produced is of a consistency capable of being molded or 105 spread in a cold state by hand. When spread

in a thin layer and exposed to the atmosphere, it cures or vulcanizes quickly, the benzol evaporating. It is very tenacious and before vulcanization readily unites with 5 and strongly adheres to leather and fabric. In the manufacture of the shoe, sufficient mixture is molded or spread in a cold state in a layer upon the insole to fill the cavity thereof, and the material intimately combines and amalgamates with the surface of 10 the insole, becoming closely and firmly united thereto. In practice the outer sole is not secured in place until some time after the layer has become vulcanized, the outer sole being firmly secured to the under surface of the layer by any of the well known cements, appropriate for the purpose.

In the drawing, I have shown an inner sole known to the trade as the "gem insole", 20 having a fabric reinforce provided with a gutta percha backing by which the same is secured to the leather. When this type of insole is employed, the under surface of the fabric reinforce is prepared for the reception 25 of the layer 4 by providing the same with a coating of liquid glass or solution of silicate of soda. When the ordinary insole without the fabric reinforce is used the layer 4 is applied directly to the leather.

The cured layer in the shoe is elastic, water repellent, non-shrinkable, not permanently conformable to localized pressures, unaffected by cold or any reasonable degree 35 of heat, it is not in any way harmful to the leather, stitching or adjacent fabric, either in the application thereof, or by the presence of injurious acids. A shoe is thus provided having a non-shiftable, permanently even, resilient tread or support for the foot 40 throughout the life of the shoe, and the water proofing qualities, durability and pliability of the shoe are materially increased.

The following is a formula which I prefer and which I have found in practice to 45 give particularly good results.

Cork dust	150	parts
Gristly crape rubber	125	"
Sulfur	12	"
50 Venetian red, or sun set lamp black	9	"
Magnesia	3	"
Gasolene, or benzol	550	"
Gutta-percha	6	"
55 Carbon-tetrachlorid	16	"

The sulfur in the mixture is instrumental in effecting a cold cure and in this is assisted by the magnesia. The tenacity and ability of the mixture to closely combine 60 with and adhere to the leather is materially abetted by the gutta-percha. Carbon tetrachlorid itself will not discolor or in any way injure the leather, the stitching of the welt, or the adjacent fabric, and is instrumental 65 in protecting these parts. It serves to main-

tain the composition cool and counteracts or prevents the natural tendency of the rubber in the composition to draw.

It will be remarked that the layer 4 in the completed shoe is characterized by the 70 absence of all injurious acids, and will not harm the leather, stitching, or adjacent fabric. The shoe is free from materials that cause squeaking and will not draw the feet.

The shoe filling material and the method 75 of manufacturing it are not claimed herein but form the subject-matter respectively of my co-pending applications Serial No. 33,264, filed June 10, 1915 and Serial No. 33,265, filed June 10, 1915. 80

What I claim is:

1. A shoe having an inner sole and an outer sole, and a composition layer in the cavity of the inner sole between the soles and firmly united thereto, said layer comprising a rubber solution, a filling material, and a vulcanizing material. 85

2. A shoe having an inner sole and an outer sole, and a composition layer in the cavity of the inner sole between the soles 90 and firmly united thereto, said layer comprising a rubber solution, a large proportion of filling material, a vulcanizing material, and carbon tetrachlorid.

3. A shoe having an inner sole and an outer sole, and a composition layer in the cavity of the inner sole between the soles and firmly united thereto, said layer comprising a rubber solution, a large proportion 100 of comminuted cork filler, a vulcanizing material, gutta percha, and carbon tetrachlorid.

4. A shoe having an inner sole and an outer sole, and a composition layer in the cavity of the inner sole between the soles, 105 said layer consisting of a rubber solution, a filling material, and a vulcanizing material, the layer of the material being united with and adhering to the surface of the inner sole. 110

5. A shoe having an inner sole and an outer sole, and a composition layer in the cavity of the inner sole between the soles, said layer consisting of a rubber solution, a filling material, and a vulcanizing material, the layer of material being united 115 with and adhering to the surface of the inner sole, the under surface of said layer being firmly connected to the outer sole.

6. A shoe having an inner sole provided 120 with a fabric reinforce, an outer sole, a composition layer in the cavity of the inner sole between the soles and firmly united thereto, said layer comprising a rubber solution, a filling material, and a vulcanizing 125 material.

7. A shoe having an inner sole provided 130 with a fabric reinforce, an outer sole, a composition layer in the cavity of the inner sole between the soles and firmly united thereto,

said layer comprising a rubber solution, a filling material, a vulcanizing material, and carbon tetrachlorid.

8. A shoe having an inner sole provided with a fabric reinforce treated with soluble glass and cemented to the inner sole, an outer sole, and a composition layer in the cavity of the inner sole adhering to the fabric reinforce, said layer comprising a rubber solution, a filling material, and a vulcanizing material.

9. A shoe having an inner sole provided with a fabric reinforce treated with soluble

glass and cemented to the inner sole, an outer sole and a composition layer in the cavity of the inner sole adhering to the fabric reinforce, said layer comprising a rubber solution, a filling material, a vulcanizing material and carbon tetrachlorid.

In testimony whereof I hereunto affix my signature in the presence of two witnesses.

ADAM H. PRENZEL.
